T. E. ADAMS,
CORNER SHIELD FOR BUILDING SIDING,
APPLICATION FILED JULY 28, 1916.

Patented Mar. 5, 1918.

UNITED STATES PATENT OFFICE.

THOMAS E. ADAMS, OF BEATRICE, NEBRASKA, ASSIGNEE TO BEATRICE STEEL
TANK MANUFACTURING COMPANY, OF BEATRICE, NEBRASKA, A CORPORATION
OF NEBRASKA.

CORNER-SHIELD FOR BUILDING-SIDING.

1,258,080.

Specification of Letters Patent.

Patented Mar. 5, 1918.

Application filed July 28, 1916. Serial No. 111,853.

To all whom it may concern:

Be it known that I, THOMAS E. ADAMS, a citizen of the United States of America, and resident of Beatrice, county of Gage, 5 and State of Nebraska, have invented certain new and useful Improvements in and Relating to Corner-Shields for Building-Siding, of which the following is a specification.

10 This invention relates to certain improvements in corner shields for building siding; and the objects and nature of the invention will be readily understood by those skilled in the art in the light of the following explanation of the accompanying drawings illustrating what I now believe to be the preferred embodiment and mechanical expression of my invention from among other formations and constructions within the 15 spirit and scope thereof.

The corner shield of my invention is characterized by nail head guards composed of annular ribs or bosses pressed in the sheet metal of the shield and forming cup-like 20 depressions through which the nail holes or perforations are centrally arranged and in which the nail heads are located after the shield is secured in place on the siding; this nail head guard formation being designed to provide approximately smooth or 25 rounded surfaces surrounding the nail heads and over which paint brush bristles can freely pass and by which said bristles will be deflected from the nail heads to prevent 30 said heads gathering surplus quantities of paint from the bristles and the consequent objectionable appearance of the resulting painted surface, and to cause any surplus paint to gather in the depressions around 35 the nail heads.

The shield of my invention is also characterized by a peculiar upper end formation which not only stiffens the shield against spreading or opening but also renders the shield applicable to drop siding. 40

The shield of my invention is also characterized by peculiar formations rendering it capable of use in finishing the corners of drop siding and avoiding the necessity 45 of employing the objectionable drop siding corner joints now commonly followed where drop sidings are used.

With these and other objects in view the invention consists in certain novel features

in construction and formation as more fully 55 and particularly set forth and pointed out hereinafter.

Referring to the accompanying drawings:—

Figure 1, is a perspective view of a portion 60 of a drop siding corner equipped with shields constructed in accordance with my invention.

Fig. 2, is a vertical sectional view on the lines 2—2, Fig. 1. 65

In the drawings, I show a corner stud 1, and drop siding boards 2, lapping the outer side faces of said stud and approximately meeting at their ends to form the siding corner. These boards are of the common 70 formation with longitudinal grooves in their bottom edges, and longitudinal tongues at their upper edges. The opposite side faces of each board are flat and parallel except where beveled off or rabbeted (see 2^a) at 75 the upper portions of their front faces.

Heretofore, the corners of buildings provided with drop siding have been finished by vertical corner boards or strips traversing and nailed to the ends of the approximately meeting siding boards but this old corner finish has always been objectionable for various reasons among which can be noted the fact that the corner strips leave 80 spaces between the outer surfaces of the 85 beveled portions 2^a, of the siding boards and the inner surfaces of the corner strips which spaces are not accessible for painting.

I provide a sheet metal corner shield to lap and approximately closely fit and cover 90 the outer surfaces of the end portions of a pair of drop siding boards at the corner of a building and to cover and bridge the joint between the end edges of said boards, and to hence avoid the necessity of employing 95 said vertical corner strips.

In the particular example illustrated, each metal corner shield is suitably formed from a single sheet metal blank to provide a pair of similar vertical wings 5, diverging 100 approximately at right angles from the central longitudinal or vertical corner angle or bending line 6 with the lower edge portion of the blank bent inwardly to form a bottom horizontal inturned flange 7, extending throughout the length of each wing 105 5 with the intermediate portion of the flange below the angle 6, preferably formed with

a tuck 8 indicated by dotted lines to stiffen the structure. This tuck formation at the junction between the diverging portions of the flange is not claimed herein and hence 5 is not fully illustrated, and described hereby.

Each wing of the shield is approximately flat and vertical so that the shield will snugly fit the flat vertical outer faces of the two boards engaged thereby, and the upper 10 end portions 9 of the two wings are depressed or curved inwardly and upwardly to conform to and snugly fit the beveled surfaces 2^a, of the upper portions of the boards and to provide the flat vertical top 15 edge portions or tongues 10, fitting the outer side faces of the top edge portions of the boards including their top edge tongues. The shield is hence formed to extend approximately throughout the full vertical 20 widths of the boards engaged thereby, with its bottom flange fitting the bottom edges of the two boards and with its upper end tongues 10 extending with the tongues of said boards into the bottom edge grooves 25 of the next set of boards above.

The depressed upper end portions 9, of the two wings 5, of the shield are joined by a longitudinal corner rib 11, that constitutes approximately a vertical continuation of the 30 angle or bending line 6 of the main body of the shield and that terminates at its upper end in a shoulder 12 adapted to approximately engage the continuous flange 7 of the next corner shield above. This vertical 35 rib 11 terminates short of the upper end tongues 10 of the shield, or in other words, does not extend to the top edge of the shield. The flat blank from which the shield is formed has a central U-shaped notch cut in 40 its upper end, so that in shaping the shield, the portion of metal between the depressed portions 11, can be gathered or pressed up to form the stiffening rib 11, and the inner corners of the tongues 10 can be approximately brought into contact above the depressed shoulder 12, that forms the upper 45 end of said rib.

By this peculiar rib formation, the upper portions of the wings of the shield are 50 braced and stiffened against opening or bending outwardly, the corner between the portions 9, is closed against passage of moisture, an attractive finish is attained, and the depressed upper end of the rib not only 55 forms a stop against undue upward adjustment of the shield but said upper end is so located below the flange of the shield above as to prevent water dripping into the upper end of the rib from the shields above.

60 The shields are secured to the siding by nails 15 which are also preferably utilized to secure the ends of the siding boards to the corner stud 1. Each shield is formed with nail holes arranged in the outer edge portions of its wings, preferably below the de-

pressed upper ends 9. In the particular example illustrated, each wing is shown formed with two nail holes in its main or body portion. Each nail hole is formed at the center of the floor or bottom of a cup-like depression 16, surrounded and in fact formed by a surrounding annular boss, rib or elevation 17, pressed up from the sheet metal of the shield. After the shields are applied, the heads of the nails 15 are located 70 down in depressions 16 and are surrounded and guarded by the deflecting ribs 17 which are designed and formed to deflect paint brush bristles from the nail heads and to prevent the nail heads scraping or collecting 75 surplus quantities of paint from paint brushes during the operation of painting the shields and siding. Heretofore, one objection against the use of metal corner shields in house construction, has been based 80 on the unsightly appearance of such shields after the house siding has been painted caused by the dried heavy streaks of paint extending down on the surfaces of the shields from each nail head. These streaks are 85 formed by the surplus paint collected from the paint brushes by the heads of the nails securing the shields. This surplus paint is not absorbed by the metal surfaces of the shields but travels down from the nail heads 90 and dries.

The ribs 17 of my invention are formed to prevent such engagement of the nail heads with the brushes as will cause this surplus deposit of paint, while the depressions 100 16 in which the heads are countersunk will retain paint around said heads and seal the nail holes.

The shields can be applied to the corner of a previously completed siding, by forcing 105 the tongues 10, of each shield upwardly along the tongues of the pair of boards to be covered and into the bottom grooves of the pair of boards immediately above, by hammer or other blows applied to the lower 110 end of the shield (at 8) until the tongues 10, are driven home. The shield can then be pressed in against the faces of the pair of boards with the flange 7 fitting the lower edges thereof, whereupon the nails 15 can 115 be applied. The shields can also be applied to the boards as the siding is built up so that the nails 15 can be utilized to secure the ends of the board to the corner stud.

It is evident that various changes and 120 modifications might be resorted to without departing from the spirit and scope of my invention and hence I do not wish to limit all features thereof to the exact disclosures hereof.

What I claim is:—

1. A metal corner shield for drop siding composed of a pair of diverging wings to fit the front flat faces of a pair of siding boards and having depressed upper ends to 130

fit the beveled upper front portions of said boards, said shield formed with a longitudinal corner stiffening rib between and joining the depressed upper portions of said 5 wings, substantially as described.

2. A metal corner shield composed of a pair of diverging wings formed to fit and cover the outer sides of the ends of a pair of siding boards, the upper portions of said 10 wings being depressed and formed with upwardly projecting flat tongues, said shield being formed with a longitudinal rib between and joining the depressed portions of

the wings below said tongues, the upper end of said rib forming a depressed shoulder. 15

3. A metal corner shield composed of diverging wings formed to closely fit and cover the outer surfaces of a pair of siding boards and to bridge the angle between the same, said shield formed with an outwardly projecting longitudinal stiffening rib at the angle between said wings, the upper end of the rib forming a shoulder. 20

Signed,

THOMAS E. ADAMS.
